United States Patent Office

Des. 227,140
Patented June 5, 1973

227,140

SERVING DISH OR SIMILAR ARTICLE

David Douglas, 1119 Lincoln Blvd.,
Manitowoc, Wis. 54220

Filed Sept. 7, 1971, Ser. No. 178,547

Term of patent 14 years

Int. Cl. D7—01

U.S. Cl. D44—15 A

FIG. 1 is a top plan view of a serving dish or similar article showing my design;

FIG. 2 is a side elevation view;

FIG. 3 is a bottom plan view; and

FIG. 4 is a sectional view taken along line 4—4 of FIG. 1.

I claim:

The ornamental design for a serving dish or similar article, as shown.
